(57) **CLAIM**

The ornamental design for a commode urine blocker, as shown and described.

DESCRIPTION

FIG. 1 is a side perspective view of a commode urine blocker which is attached to a toilet seat, showing my new design.

FIG. 2 is a side perspective view of the commode urine blocker.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines shown in the figure represent a toilet seat and form no part of the claimed design.
